Attorney

UNITED STATES PATENT OFFICE.

LEE J. BLACK, OF BEAUMONT, TEXAS.

COMBINED GUIDE PLUG AND FLOAT VALVE FOR WELL CASINGS.

Application filed July 19, 1927. Serial No. 206,978.

This invention relates to a combined guide plug and float valve for well casings.

An important object of the invention is to produce a device of this character which may be very readily attached to the casing shoes of the well casing without in any manner altering the structure thereof, and which is capable of use with casing shoes, the internal diameters of which vary between certain limits.

A further object of the invention is to provide a device of this character of such construction that the back pressure valve is located above the upper end of the guide plug and accordingly this guide plug may be provided with an axial bore which will serve to guide the fluid in a solid stream against an obstacle.

A still further object of the invention is to provide a structure of this character, wherein the back pressure valve is so located that it does not interfere with the spudding out of bridges formed by cavings in the bore with the casing.

These and other objects I attain by the construction shown in the accompanying drawings, wherein for the purpose of illustration is shown a preferred embodiment of my invention and wherein:—

Figure 1 is a vertical sectional view of a combined guide plug and float valve constructed in accordance with my invention;

Figure 2 is a section on the line 2—2 of Figure 1.

Referring now more particularly to the drawings, the numeral 10 generally designates a casing shoe of a well casing which has its lower end face downwardly and outwardly tapered, as indicated at 11, in the usual construction of such devices.

In accordance with my invention, I provide a hollow plug 12 having a rounded lower end wall 13, which is provided axially with an opening 14. The plug has an external diameter the same as that of the casing shoe and has upon its upper end a reduced extension 15, which is connected with the main body of the plug by an offset, providing an external shoulder 16 having the same taper as the lower face of the casing shoe. The interior of the extension has a downwardly tapering threaded bore 17 and the extension above the shoulder 16 is slit at intervals, as indicated at 18.

A spider 19 is provided, having directed therethrough centrally the stem 20 of a valve

21, which seats against the lower face of the spider to seal ports 22 formed therein against the upward passage of fluid. The upper end of the stem has a spring seat 23 against which seats one end of a spring 24 surrounding the stem and having its lower end abutted against the spider. The outer face of this spider has a taper similar to that of the bore of the plug extension 25 and is threaded for the coaction of the threads thereof.

It will be obvious that by seating the plug in the lower end of the casing shoe and threading the spider thereinto, the upper end 70 of the extension will be expanded and come into tight frictional engagement with the walls of the casing shoe to connect the plug thereto. It will also be obvious that since the valve controlling the passage of water is 75 located well above the upper end of the plug, the fluid passing this valve will unite and form a solid stream in passing from the opening 14, so that it will provide an efficient washing jet for use in settling the pipe. Furthermore, a valve located as described 80 will be free from the damage ordinarily sustained by such valves during the lowering operation where the valve is located at the lower end of the shoe. It will be obvious 85 that the expansion of the upper end of the plug will enable the plug to be adapted to casing shoes wherein the internal diameter varies slightly as, for example, between two casing shoes intended for use with the same 90 sized casings but with casings having different weights.

Since the construction hereinbefore set forth is capable of a certain range of change and modification without materially departing from the spirit of the invention, I do not limit myself to such specific structure except as hereinafter claimed.

I claim:—

1. In a combined guide plug and float valve for well casings, a hollow guide plug having an axial aperture in its lower end and having at its upper end an extension adapted for engagement in the bore of a casing shoe, said extension being expandable, a ported spider engageable in said upper end to expand the same into clamping engagement with the casing shoe and a downwardly opening check valve controlling the ports of the spider.

2. In a combined guide plug and float valve for well casings, a guide plug having

- an axial port in its lower end and having at its upper end an extension to engage in and substantially fit the bore of a casing shoe, said extension having a tapered threaded bore, a ported spider having a threaded periphery for engagement in the tapered bore of the extension and a check valve coacting with the ports of the spider, said extension being slit to permit expansion thereof by 10 said spider.
3. In a combined guide plug and float valve for well casings, a guide plug having an axial port in its lower end and having at its upper end an extension to engage in and 15 substantially fit the bore of a casing shoe, said extension having a tapered threaded bore, a ported spider having a threaded periphery for engagement in the tapered bore of the extension and a check valve coacting 20 with the ports of the spider, said extension being slit to permit expansion thereof by said spider, the connection of said extension with the plug embodying a shoulder confronting and fitting against the lower end of 25 the casing shoe.
4. In a combined guide plug and float valve for well casings, a hollow guide plug having an axial aperture in its lower end and having at its upper end an extension 30 adapted for engagement in the bore of a casing shoe, said extension being expandable, a ported spider engageable in said upper end to expand the same into clamping engagement with the casing shoe and a downwardly opening check valve controlling the ports 35 of the spider, the connection of said extension with the body of the plug providing a shoulder confronting and fitting against the lower end of the casing shoe.
5. In a combined guide plug and float valve for well casings, a hollow guide plug having an axial aperture in its lower end and having at its upper end an extension adapted to enter the bore of the casing shoe and having its walls slotted, the bore of 40 said tubular extension tapering downwardly and being screw-threaded, a ported spider having a downwardly tapering peripheral wall screw-threaded for engagement with the wall of the bore of the extension and an 45 upwardly closing check valve controlling the ports of the spider.
6. In a combined guide plug and float valve for well casings, a hollow guide plug having an axial aperture in its lower end and having at its upper end an extension adapted to enter the bore of the casing shoe and having its walls slotted, the bore of 50 said tubular extension tapering downwardly and being screw-threaded, a ported spider having a downwardly tapering peripheral wall screw-threaded for engagement with the wall of the bore of the extension and an 55 upwardly closing check valve controlling the ports of the spider.
